CLAIM

The ornamental design for a container package, as shown and described.

DESCRIPTION

FIG. 1 is a perspective view of the container package showing our new design;

FIG. 2 is a top plan view thereof, the bottom plan view being identical thereto;

FIG. 3 is a right side elevational view thereof, the left side being identical thereto; and

FIG. 4 is a front elevational view thereof, the rear elevational view being identical thereto.

In the figures, the dashed lines represent score lines.
